[57] CLAIM

The ornamental design for a water and tapered sponge washer structure or similar article, as shown.

DESCRIPTION

FIG. 1 is a perspective view of the water and tapered sponge washer structure showing my new design;

FIG. 2 is a top plan view thereof;

FIG. 3 is a side elevational view thereof;

FIG. 4 is a bottom plan view thereof;

FIG. 5 is an end plan view thereof;

FIG. 6 is an end view directly opposite the view of FIG. 5.

FIG. 1
